CLAIM

The ornamental design for a product tray, as shown and described.

DESCRIPTION

FIG. 1 is a top perspective view of a product tray, showing our new design;

FIG. 2 is a bottom perspective view of the product tray of FIG. 1;

FIG. 3 is a top view of the product tray of FIG. 1;

FIG. 4 is a bottom view of the product tray of FIG. 1;

FIG. 5 is a front view of the product tray of FIG. 1;

FIG. 6 is a rear view of the product tray of FIG. 1;

FIG. 7 is a left side view of the product tray of FIG. 1; and,

FIG. 8 is a right side view of the product tray of FIG. 1.

1 Claim, 4 Drawing Sheets
